(No Model.)

F. X. PAYMENT & J. C. HARTIG.
SASH BALANCE.

No. 545,609.

Patented Sept. 3, 1895.

UNITED STATES PATENT OFFICE.

FRANCOIS XAVIER PAYMENT AND JOHN C. HARTIG, OF CHICAGO, ILLINOIS.

SASH-BALANCE.

SPECIFICATION forming part of Letters Patent No. 545,609, dated September 3, 1895.

Application filed July 13, 1894. Serial No. 517,486. (No model.)

To all whom it may concern:

Be it known that we, FRANCOIS XAVIER PAYMENT, a subject of the Queen of Great Britain, and JOHN C. HARTIG, a citizen of the 5 United States, residing at Chicago, county of Cook, and State of Illinois, have invented a new and useful Improvement in Pulleys, of which the following is a specification.

Our invention relates to suspending pulleys 10 and the like particularly adapted for sash-supports.

The object is to provide a simple easily-operating sash-supporting pulley, which will support the sash in any desired position and 15 which can be applied without particularly disfiguring either window frame or sash and which will leave few parts exposed.

Our invention is illustrated in the accompanying drawings, wherein—

20 Figure 1 is a section view through a portion of a window casing and sash, showing a side elevation of my device in position for use. Fig. 2 is a cross-section through the pulley and case. Fig. 3 is an inside view of the plate.

25 Like parts are indicated by the same letters in all the figures.

A is the window-frame, which is mortised or worked out at A' to receive the pulley-case.

B is the sash, which is mortised at B' to receive 30 the block B² on the end of the supporting-ribbon.

C is a plate, preferably secured at the mouth of the aperture or mortise, so as to cover the same, and having the inwardly-projecting 35 ring-shaped portion C' with the side parts C², thus together forming the case for the pulley proper.

C³ is a shaft cut away at C⁴ and fitted into the side of the pulley-case so as to be fixed 40 and not to rotate.

C⁵ is the pulley-flange, which presents a flat surface projecting up into the contracted outer annular space of the pulley-case, and it is mounted and supported upon the pulley 45 proper C⁶, which is loose upon the shaft C³. It is mounted upon the ring C⁷.

D is a metallic suspending ribbon secured at one end upon the cross-pin D', which is let into the slot D² in the lower end of the block 50 B². The ribbon passes through the block B² and about a part C⁶, and is finally secured to the pin D³ in the side of the pulley. A coiled

spring E is placed within the pulley secured at one end to the shaft C³, which is fixed at the other to the pin E', which rotates with the 55 pulley. The pulley is preferably closed at one side by a plate and at the other by a cross-bar F, which is let into the edge of the pulley, as indicated in Fig. 1, the pin E' being screw-threaded and screwed into the pulley so as to hold the end of the cross-piece F in position.

G is an aperture in the plate C, through which the pulley slightly projects and through which the ribbon runs.

The use and operation of our invention are 65 as follows: A pulley should be associated with each sash, and there may be two with each sash, one on each side. These pulleys are preferably located, for example, near the top of such sash when it is at its lowest position. The recess or slot in the side of the sash 70 is preferably placed at the lower end of the sash, or in order that an opening may be made on the outer edge or face of such sash so as not to be visible within the room, but to be covered and concealed, when the sash is in position, 75 by the strip on the side of the window case or frame. The pulley and case are situated in a suitable recess in the side of the window case or frame. When the sash is placed in 80 position, the block at the end of the ribbon is placed in the recess in the sash. The sash may then be moved to any desired position, and the relation between the strength of the ribbon, the strength of the spring, the weight 85 of the sash, and the friction of the parts is such that the sash will stay in any desired position. If the window is pressed downwardly, for example, the tendency is to draw the ribbon out and this coils the spiral spring, 90 and when, the parts being in such position, one desires to raise the sash the spring, tending to recoil when the load is partly lifted, will assist in restoring the parts to their normal condition.

95

We claim—

1. The combination of a window sash having a recess in one side opening at the outer surface of the sash, a block adapted to fit into the recess in the sash, a metallic ribbon having one end attached to said block the other end passing through an aperture in a plate attached to the window frame and being fastened to a pulley placed in a recess in said 100

frame, said plate projecting outwardly above said aperture so as to form a stop for said block, and a spiral spring coiled within said pulley, one end of said spring being fastened 5 to the case of the pulley so as to revolve with it, the other end being fastened to a fixed central pivot, substantially as described.

2. The combination of a window sash having a recess in one side opening at the outer 10 surface of the sash, a block adapted to fit into the recess in the sash, a metallic ribbon having one end attached to said block, the other end passing through an aperture in a plate attached to the window frame and being fastened 15 to a pulley placed in a recess in said

frame, said pulley projecting slightly through said aperture, a spiral spring coiled within the pulley one end of said spring being fastened to a threaded pin or screw rotating with the pulley, the other end being fastened 20 to a fixed central pivot, and a side bar removably connected to said threaded pin and pivot and adapted to prevent the spiral spring being withdrawn from or inserted in the pulley.
